UNITED STATES PATENT OFFICE.

GEORGE DAWSON, OF CARDINGTON, OHIO.

OVERALLS.

SPECIFICATION forming part of Letters Patent No. 278,106, dated May 22, 1883.

Application filed December 30, 1882. (No model.)

To all whom it may concern:

Be it known that I, GEORGE DAWSON, of Cardington, in the county of Morrow and State of Ohio, have invented certain new and useful Improvements in Overalls; and I do hereby declare the following to be a full, clear, and exact description of the invention, such as will enable others skilled in the art to which it pertains to make and use it, reference being had to the accompanying drawings, which form part of this specification.

My invention relates to an improvement in overalls; and it consists in uniting the pants and jacket together at their backs, so as to form practically one piece, but leaving them disconnected at their front edges, except by buttons or other suitable fasteners, so that whenever the suit is to be put on the jacket can be disconnected from the pants in front, so as to leave the person greater freedom of movement in pulling the suit on.

The object of my invention is to unite the jacket and pants together around their rear edges, so as to form but a single garment, which can be donned with greater ease and rapidity than where the two parts are made entirely separate and have to be fastened on each other all the way round by means of buttons or other fastenings.

Figure 1 is a front elevation of a suit of overalls embodying my invention. Fig. 2 is a rear view of the same. Fig. 3 is a vertical cross-section taken through on the line where the two parts are buttoned together at the front.

A represents the pants, and B the jacket. Each of these parts may be of any suitable construction that may be preferred, and are united together in any suitable manner at their

backs, so as to form practically a single garment. The jacket and pants are entirely disconnected at their front, so that the jacket can be opened its full width, for the purpose of allowing greater freedom of movement when the person is donning the suit. One part is provided with suitable button-holes and the other part is provided with buttons, so that the pants can be buttoned across the front after the suit is on, and thus unite the parts together across this point, as shown in Fig. 3.

The great advantage of the construction above described consists in the ease with which the whole suit can be donned at once, in dispensing with the usual fastenings around the back, and in dispensing with the suspenders and other such devices for the support of the pants. They are comfortable, convenient, and durable, and from their peculiar cut and make hang directly and evenly from the shoulders and take off all strain from the under-clothes and suspenders.

Having thus described my invention, I claim—

Overalls consisting of a jacket and pants, which are united together at their backs, so as to form practically a single garment, and which pants and jacket are disconnected at their front edges, so that the jacket can be opened to its full width independently of the pants, substantially as shown and described.

In testimony whereof I affix my signature in presence of witnesses.

GEORGE DAWSON.
